(57) **CLAIM**

The ornamental design for an extractor base module hood, as shown and described.

DESCRIPTION

FIG. 1 is a perspective view of an extractor base module hood showing my new design;

FIG. 2 is a top elevational view thereof;

FIG. 3 is a front elevational view thereof;

FIG. 4 is a rear plan view thereof;

FIG. 5 is a left side elevational view thereof; and,

FIG. 6 is a right side elevational view thereof.

The details shown in broken lines in the figures are shown for illustrative purposes only and form no part of the claimed design.
